UNITED STATES PATENT OFFICE.

CLARENCE E. SCHAFFNER, OF CINCINNATI, OHIO.

DESIGN FOR A DISPLAY-CASE.

No. 39,917.

Specification for Design.

Patented April 13, 1909.

Application filed November 2, 1908. Serial No. 460,794. Term of patent 3½ years.

To all whom it may concern:

Be it known that I, CLARENCE E. SCHAFFNER, a citizen of the United States, residing at Cincinnati, in the county of Hamilton and State of Ohio, have invented a new, original, and ornamental Design for Display-Cases, of which the following is a specification, reference being had to the accompanying drawing, forming part thereof.

The figure is a perspective view of the display-case, showing my new design.

I claim:

The ornamental design for a display-case, as shown.

CLARENCE E. SCHAFFNER.

Witnesses:

JOHN ELIAS JONES,
NORMA KEISER.
